UNITED STATES PATENT OFFICE.

ARON M. BEAM, OF DENVER, COLORADO, ASSIGNOR TO THE AMERICAN CONTINUOUS RETORT COMPANY, OF DENVER, COLORADO.

MUFFLED ORE-CONVERTING APPARATUS.

1,299,661.

Specification of Letters Patent.

Patented Apr. 8, 1919.

Application filed December 10, 1917. Serial No. 206,466.

To all whom it may concern:

Be it known that I, ARON M. BEAM, a citizen of the United States of America, residing at the city and county of Denver and State of Colorado, have invented a new and useful Muffled Ore-Converting Apparatus, of which the following is a specification.

This invention relates to improvements in continuous feed muffled ore converting and 10 roasting apparatus.

The objects of the invention are:

First: to provide a continuous feed muffled ore roasting and converting apparatus, adapted to volatilize the deleterious elements 15 of refractory ores.

Second: to provide a double unit muffled ore converting and roasting apparatus in which two inclosed ore converting chambers or ovens are arranged one above the other, 20 and are connected at their rear ends by a feed spout, means being provided for continuously moving ore from the forward end of the upper chamber to and through the said feed spout and along the lower chamber to a discharge hopper at its forward end, a continuous heat-conveying flue being arranged which extends beneath the lower chamber and between the lower and upper 25 chambers, and over the upper chamber, said flue connecting with a combustion chamber at one end of the apparatus and with a stack at its opposite end, the said apparatus being adapted to convert refractory ores to a cyaniding and also to an amalgamating condition. 30

These objects are accomplished by the mechanism illustrated in the accompanying drawings, in which:

Figure 1 is a vertical longitudinal sectional view of an ore converting apparatus constructed in accordance with my invention. 40

Fig. 2 is a horizontal sectional view on the line 2—2 of Fig. 1, the top of the lower unit being partly broken away.

Fig. 3 is a transverse vertical sectional view—enlarged—through the fire box end 45 of the apparatus.

Fig. 4 is an enlarged horizontal sectional view through the rear portion of the apparatus. 50

Fig. 5 is a perspective view of a portion of one of the ore scraping devices.

Fig. 6 is a front view of a portion of a modified form of one of the scrapers.

Fig. 7 is a side view of the same; and 55

Fig. 8 is a horizontal sectional view on the line 8—8 of Fig. 7.

Referring to the accompanying drawings:

The numeral 1 indicates a structure preferably made of brick and comprising side 60 and end walls and an arched roof, the structure being of suitable dimensions for the purpose required.

Adjacent the front end wall 2 is a transverse fire wall 3, which is high enough to 65 form between it and the end wall 2 an ash pit 4, and a fire box 5, the latter being roofed over with fireproof slabs 6. The ash pit 4 and fire box 5 open out through the side 7 of the structure, and are provided with doors 70 8 and 9, respectively, and grate bars 10 extend transversely across the bottom of the fire box and are supported at their rear ends upon a bar 11, secured in the side wall 12, and at their forward ends upon a metal 75 frame 13, which fits in the side wall 7 and to which the doors 8 and 9 are hinged.

The fire wall 3 terminates a suitable distance below the slabs 6 to form an opening 80 between the fire box and a flue 14, which extends beneath the lower bed or hearth 15, as will be understood by reference to Fig. 1. The bed 15 is preferably in the form of a metal plate, which extends from one side wall to the other, the side edges thereof being upturned as shown. This bed rests at its forward end on the slabs 6 and is supported at intervals throughout its length by cross bars 16, and terminates a short distance from the rear wall 17. A second metal 90 plate or ceiling plate 18 is supported between the side walls a suitable distance above the bed 15, and these two plates 15 and 18, with the side walls, constitute the lower converting chamber or oven. This 95 chamber is closed at its rear end by a plate 19, which is spaced far enough from the rear wall to provide a passage 20, which forms a continuation of the flue 14. The forward end of the chamber is closed by doors 21, 100

Fig. 2 is a horizontal sectional view on the line 2—2 of Fig. 1, the top of the lower unit being partly broken away.

which permit access to the chamber for any purpose, such as the removal and replacement of the bed or the removal of the scrapers to be presently described. The 5 chamber is provided with an ore outlet chute 22 at its forward end, which extends up at an angle through the front wall, its upper end being flush with the level of the bed.

The upper converting chamber is constructed in the same manner as the lower 10 chamber and comprises a bed or hearth 23, which is supported far enough above the ceiling plate 18 of the lower chamber, to provide a flue 24; and a ceiling plate 25 is 15 supported above the bed 23 to form a chamber of the same dimensions as the lower chamber. The front end of this chamber is closed by a plate 26, which is spaced from the front wall to form a continuation 27 of 20 the flue 24, and the flue 27 opens into a flue 28, which is formed by the ceiling plate 25, and the arched roof 30 of the structure, the flue 28 having an outlet stack 29. While 25 the roof 30 of the structure is shown as of brick work, the same may be of sheet metal if desired. The rear end of the upper converting chamber is closed by a suitable door 30 or cover 26A, which permits access to the chamber when required.

30 The rear ends of the upper and lower chambers are connected by a spout or chute 31, which extends through the flue 24, and as this spout is practically the same width as the flue, and would therefore close communication between this flue and the flue 20, it is necessary to form lateral flues 32 in 35 the side walls, as clearly shown in Figs. 2 and 4, which permit the heated air passing up through the flue 20, to pass around the 40 ends of the chute 31, and into the flue 24.

Thus, the flues 14, 20, 24, 27, and 28, form a continuous passage from the fire box 5, to the stack 29, and convey the heated air below the lower chamber, and between the 45 two chambers and above the upper chamber, thus subjecting the ore in each chamber to heat from above and below simultaneously.

A feed hopper 33, supplies ore to the forward end of the upper chamber, the hopper 50 having a spout which passes down through the arched roof of the structure and into the upper chamber, and the ore thus fed to the upper chamber, is carried back to and through the spout 31, to the rear end of the 55 lower chamber and thence forward to the outlet chute 22 in the following manner:

Along the sides of the chambers adjacent to the ceiling plates 18 and 25, are secured tracks or slideways 34, in the form of angle 60 bars which extend substantially the length of the chambers, and upon the slideways of each chamber is supported the ore scraping mechanism which is arranged in the following manner:

65 Supported upon the slideways 34 of each

chamber are cross bars 35, to which are secured parallel longitudinal angle bars 36, each pair of which terminate at their rear ends in right angled portions which are again bent at right angles to provide parallel members 37 and 38 respectively, which lie close together and extend out through the rear end of the structure, the members 37 extending through an aperture in the door 26A, while the members 38, extend through an aperture in the adjacent end wall. The bars 36 of each pair, are connected at suitable intervals, by rods 39, and upon each rod is pivotally suspended a pair of hanger arms 40; which extend nearly to 70 the hearth or bed, the lower end portions of the arms in the upper chamber being inclined slightly toward the rear end of the chamber, while the corresponding portions of the arms in the lower chamber are inclined toward the forward end thereof, and to the inclined portions of each pair of oppositely disposed arms in each chamber, is secured a scraper 41, in the form of a thin metal blade or plate which extends the whole width 75 of the hearth, as is most clearly shown by Fig. 3, the upper scrapers being arranged to move the ore rearward, while the lower scrapers are arranged to move it forward.

The swinging connection of the arms 40 with the rods 39, and the inclination of the scrapers, causes the scrapers to slide back over the ore on the bed, during the inoperative or non-scraping movement of the scraping mechanisms, but on the reverse movement 90 of the said mechanisms, the scrapers engage and move the ore forward, and they are limited in their backward swinging movement by stops 40A on the arms 40, which engage the under edges of the bars 36, as clearly 95 shown in Fig. 3. The two scraper mechanisms are reciprocated in unison and in the following manner:

The rearwardly extended portions 37 and 38 respectively, of the scraper-supporting bars 36, may be connected in any preferred manner, but as illustrated in Fig. 1, they are connected by a triangular plate 42, the base portion of which is secured between members 38, while its apex portion is secured between the members 37. The lower end of the plate 42, terminates in lateral flanges 43, which rest upon slideway portions of parallel, horizontal bars 44, which are suitably connected at their inner ends to 115 the adjacent end wall of the structure, while their outer ends are supported by bars 45, and braced against lateral movement by bars 46, as shown.

Guide bars 47, are secured to the bars 120 44, and act in conjunction with them to form guideways for the flanges 43, of the plate 42, as will be understood by reference to Fig. 2.

Between the ends of the arms 38, is piv- 125

totally secured the inner end of a connecting rod 48, the outer end of which is connected to the crank portion of a shaft 49, which is mounted in bearings, 50 on the bars 44, and one end of this shaft carries a pulley 51, which is adapted to be belted to a power driven pulley, not shown. The scraper plates 41 are rigidly secured to the arms 40, but in Figs. 6, 7 and 8 I have illustrated a modification in the form of a scraper 52, which is pivotally connected to hanger arms 53, the scraper being provided with apertured ears 54, which straddle the lower portion of the arm which is also apertured and a pivot pin 55, is passed through the apertures in the ears and arm. The scraper is slotted as shown at 56, to permit the scraper to tilt backward on its inoperative movement that portion of the arm below the pivot limiting the forward tilting movement of the scraper to the position shown in Fig. 7, and the scraper rocks by gravity into this position, after being tilted backward, as the pivot pins 55 are above the longitudinal center of the scraper. Air may be admitted to the lower chamber during the converting process, by means of a pipe 57, as shown in Fig. 1.

In operation a fire is started in the firebox 5 and the heated air takes the course around to converting chambers as indicated by the arrow, in Fig. 1, the slabs 6 preventing the forward portion of the hearth 15, from being subjected to the intense heat from the fire box. Ore which has been reduced to the necessary degree of fineness is then fed to the hopper 33, and thence into the forward end of the upper chamber; the scrapers are then set in motion and the ore in this chamber is carried rearward intermittently as the upper scrapers move rearward, until the ore in advance of the rearmost scraper, discharges through the spout 31, into the lower chamber directly in front of the rearmost scraper and the ore entering the lower chamber is carried forward in the same manner until it discharges through the outlet hopper 22. During the rearward movement of the ore over the bed 23, it is subjected to the heat from the flues 24 and 28, and is delivered to the lower chamber in a very hot or partially roasted condition, and by the time it discharges from the lower bed, it is in a thoroughly roasted condition.

The improved ore roasting and converting apparatus above described, liberates the different metals in refractory ores, so that each metal can be recovered by itself.

Having described my invention, what I claim as new and desire to secure by Letters Patent, is:

1. In an apparatus of the character described, the combination with a pair of ovens arranged one above the other and means for applying heat to the under and upper side of

each oven, said ovens being connected by a chute at one end, of slideways on opposite sides of each oven, frames slidably mounted on said slideways and connected to move in unison, spaced rods carried by said frames, 70 a pair of depending arms pivotally mounted on each rod, a scraper secured to each pair of arms, the scrapers in one oven being oppositely inclined from those in the other oven, stops on said arms which engage the frames 75 and prevent movement of the arms during the operative movement of the scrapers, a feed hopper at the forward end of the upper oven, a discharge chute at the forward end of the lower oven, and means for reciprocating the frames.

2. In an apparatus of the character described, the combination with ovens arranged one above the other and connected at one end, a continuous flue extending below the lower 85 oven, between the two ovens and above the upper oven, and being connected at one end with a combustion chamber, and with a stack at its other end, of slideways on opposite sides of the ovens, cross bars mounted on the 90 slideways, and longitudinal parallel bars secured to the cross bars, the longitudinal bars in one oven being connected with those in the other oven to move in unison, spaced rods connecting each pair of longitudinal bars, a 95 pair of depending arms in swinging engagement with each rod, and a scraper secured to each pair of arms, the scrapers of one set being oppositely inclined from those of the other set, stops for limiting the arms to a 100 vertical position on their scraping movement, means for reciprocating the longitudinal bars whereby the scraping action of one set of scrapers is simultaneous with the non-scraping action of the other set, means for feeding 105 ore to the front end of the upper oven, and a discharge hopper at the front end of the lower oven.

3. In an apparatus of the character described, the combination with a structure 110 comprising side and end walls, and a roof, and having a combustion chamber at one end and a stack at the other end, of plates extending from side wall to side wall to form a lower oven, the rear end of which is closed 115 and is spaced from the rear end wall, plates extending from side wall to side wall to form an upper oven, the forward end of which is closed and spaced from the adjacent end wall, a flue space being left below the lower oven 120 between the two ovens and between the upper oven and the roof, said ovens being connected at their rear ends by a spout which extends through the separating flue, frames slidably mounted in each oven, having portions extending through the rear end wall of the structure, a plurality of pairs of oppositely arranged depending arms pivotally connected to said frames, a scraper blade connecting each pair of depending arms and disposed 130

slightly above the bottom of the oven, the scrapers in the upper oven being oppositely disposed from those in the lower oven, a slideway, a bracket connecting the portions of the frames extending through the rear wall, and mounted in said slideway, means for reciprocating said bracket, and stops for limiting the swinging movement of the

scraper arms on the forward movement of the scraper supporting frames.

10

In testimony whereof I affix my signature in presence of two witnesses.

ARON M. BEAM.
